UNITED STATES PATENT OFFICE

WILLIAM J. HARR, OF DENVER, COLORADO

ROCK CRUSHER

Application filed June 6, 1928. Serial No. 283,363.

My invention relates to crushing, grinding or pulverizing machines and its principal object resides in providing a mechanism of simple, practical and highly efficient construction, particularly adapted for crushing, pulverizing, sizing or sliming rock, coal and other substances too numerous to mention.

Another object is to provide a crushing machine adapted for the separation of values from their gangue in the material while it is being disintegrated.

Another object of the invention is to provide a machine of the above described character, capable of crushing materials in either a wet or a dry condition, it being a distinctive feature of the invention that the operating parts of the machine can not "gum", since gumbo and muck are washed away in the operation.

Another object of the invention resides in providing a crushing machine that is perfectly balanced throughout the movement of its operating elements, a further object is to provide means for varying the crushing action by the use of a weighing element that can be regulated to increase or decrease the pressure exerted by the crushing elements of the machine, upon the material under treatment, and still further objects reside in details of construction and novel and advantageous arrangements and combinations of parts, as will fully appear in the course of the following description.

In the accompanying drawings in the several views of which like parts have been similarly designated,

Figure 1 represents a plan view of my improved crushing machine;

Figure 2, a partially sectional side elevation of the same, looking in the direction of the arrow A, in Figure 1;

Figure 3, an end-elevation of the machine, partially in section, looking in the direction of the arrow B in Figure 1, and

Figure 4, a sectional elevation of one of the mortars included in the construction, showing a modified form.

The machine, as shown, comprises a base

thereof for the support of two cooperating crushing units. Each frame has four uprights 6 of angle-section, connected by horizontally disposed sills 7 and the frame may be otherwise connected or braced in any desired manner.

Each of the crushing units comprises a trough-shaped mortar 8 supported upon the sills of the respective frame by means of outwardly projecting flanges 9. The mortar has between parallel side-walls 14, a concaved bottom 10 preferably formed in the arc of a circle, the interior surface of which may be reinforced by means of a correspondingly shaped wear plate 12 of shorter width. The mortar has in the center of its bottom, a sump and outlet 13 for the discharge of crushed material and it has in one of its side-walls an overflow-outlet 15 through which slimes, tailings and fine solids in suspension are carried off.

A feed device for each crushing unit consists of a hopper 16 and diverging spouts 17, the lower vertical portions of which are slideable between the upright angle bars 6 of the respective supporting-frame.

The spouts feed the material to the mortar at the ends thereof to pass into the spaces between the crushing block and the concave surface of the mortar at opposite sides of the point of contact of the same, and the elevation of the outlets of the spouts may be varied in accordance with the nature of the material under treatment.

The material may be fed into the hopper from a launder 18 and water or other liquid may be added to the material through a pipe 19. The grinding elements of the machine consists of blocks 20 loosely supported in the concaved mortars and having arcuate undersurfaces 22 of smaller radius than the arcuate bottoms of the mortars, that permit of a rocking movement of the blocks about a central point of contact.

The blocks of the two grinding units may be provided with wear-plates 21 and they are connected for simultaneous operation by means of angle bars 23. It is to be understood that the wear plates of both the mortars and the grinding blocks may be detachable.

so that they can be renewed in case of wear or breakage.

Supported on the connecting-bars of the grinding blocks, between the two units, is an open box 24 that extends lengthwise in substantially parallel relation to the mortars in the plane of the rocking movement of the grinding element. The box is intended to carry the weight required in the crushing action of the blocks upon the material in the mortars. The weight may consist of rocks, stones, scrap-iron or other ponderous matter, and it can be varied at will by merely adding to the contents of the box or removing part thereof as may be desired. The box, furthermore, functions as a means for connecting the crushing element as an entirety with the operating mechanism of the apparatus. This mechanism consists of a cross-head 25 mounted for vertical reciprocation on upright standards 26 by means of sleeves 27. The cross-head is connected at an end of the weight box by means of pins 28, and it has a transverse slot 29 for its operative connection with the driving-element of the mechanism.

The pins 28 are fastened at an end of the box and project through apertures of the crosshead, of hour-glass form, that permit of a rocking motion of the box with relation to the crosshead.

The drive-shaft 30, carrying a pulley 31, is mounted for rotation in pedestals 32 on the base of the machine, and it has at one end, a crank 33 the wrist 34 of which travels in the transverse slot of the cross-head. The pulley of the shaft may be connected with any conveniently located source of power.

In the operation of the machine, the rotary movement of the shaft causes the crosshead to reciprocate in a vertical direction and the reciprocal motion of the crosshead produces an oscillatory or rocking motion of the crushing blocks in their respective mortars through the intermediary of the weight-box. The material fed through the spouts 17 into the mortars enters into the spaces between the concave bottom surfaces of the mortars and the convex bottoms of the respective grinding blocks, alternately at opposite ends thereof and is comminuted and disintegrated by the rocking movement of the blocks. A crushing action thus takes place alternately at opposite sides of the rocking or oscillating crushing element and the intensity of the action is determined to a great extent by the weight contained in the box 24.

It is of course desirable that this weight does not shift and solids are for this reason, particularly adapted for the purpose. However, a liquid might be used provided that the container be closed at its top and completely filled.

The material in the mortars as it is being comminuted works in under the blocks into the sumps 13 while the water overflowing

through the outlets 15 carries off the tailings. The matter collected in the sumps contains the values and the sumps may be closed by means of removable screw-caps 35 as shown in the drawings, or the matter discharged through the central outlets of the mortars may be conveyed to any other receptacle through conduits connected with the outlets.

The mortars may be supplied with mercury for the purpose of amalgamation for the extraction of the metals from the material, or the bottom surfaces of the mortars beneath the crushing-members may be grooved as indicated at 36 in Figure 2, to catch and retain the fines.

It will be apparent that the weight on the crushing element is uniform under all conditions and that the operating parts of the machine are evenly balanced at each point of the operative movement.

A modified construction of the mortar has been illustrated in Figure 4. The bottom of the mortar is perforated at 38, and a spout 37 beneath the perforated portion of the bottom guides the material passing through the apertures into a subjacent receptacle.

The modified form is particularly useful in sizing the material pulverized in the operation of the machine.

Having thus described my invention what I claim and desire to secure by Letters Patent is:

1. In a crushing machine, mortars, rocking crushing means in the mortars, bars supported by and extending between the crushing means, a weight box supported on the bars between the crushing means, and operating mechanism acting upon the weight box to rock the crushing means.

2. In a crushing machine, mortars, rocking crushing means in the mortars, bars between the crushing means, a weight box on the bars, and mechanism to effect a vertical reciprocating motion to the weight box, and thereby rock the crushing means.

In testimony whereof I have affixed my signature.

WILLIAM J. HARR.
